UNITED STATES PATENT OFFICE.

FREDERICK Y. JENSEN, OF EPHRAIM, UTAH.

FLOUR-SIFTER.

1,279,874.

Specification of Letters Patent. Patented Sept. 24, 1918.

Application filed June 8, 1918. Serial No. 238,938.

To all whom it may concern:

Be it known that I, FREDERICK Y. JENSEN, a citizen of the United States, residing at Ephraim, in the county of Sanpete and 5 State of Utah, have invented certain new and useful Improvements in Flour-Sifters, of which the following is a specification.

This invention relates to flour sifters and has for its primary object to provide a sifter 10 constructed to cause a combined oscillatory and vibratory movement to be imparted to the sifting element when the sifter is in use.

One of the objects of the invention is to provide a flour sifter of this character which 15 will operate to sift only the fine flour and which will retain any impure particles so that they will not be mixed with the sifted flour as sometimes happens with rotary types now commonly employed which tend 20 to force impurities through the screen and mix them with the sifted flour.

The invention also aims to provide a structure that will tend to hold the flour against 25 its tendency to move with the sifting screen when the latter is oscillated so that the combined vibrating and oscillating of the sifter will expedite the sifting of the flour.

A further object of the invention is to 30 provide a device of this character which consists of comparatively few parts and is simple in construction but durable and well adapted to withstand the rough usage to which devices of this character are ordinarily subjected.

35 For a full description of the invention and the advantages and merits thereof reference is to be had to the following description and accompanying drawings, in which:—

Figure 1 is a vertical section through a 40 sifter constructed in accordance with my invention.

Fig. 2 is a detail section through a portion of the sifter.

The sifter 1 is of the same general body 45 construction as is now commonly employed and is provided with a handle 2 for facilitating manipulation.

Approximately intermediate its length, the cylindrical wall of the body is provided 50 with an annular bead 3 formed by pressing inwardly as shown to advantage in Fig. 1. The interior annular bead thus formed acts as a shelf to support a ring 4 which fits snugly in the body so that it will be prevented from rotating when the sifter is in 55 operation. This ring includes the annular

flange which rests above the interior bead 3 and the corrugated relatively wide flange 5 depending from the ring 4. The flange 5 is crimped to form the corrugations the purpose of which will be presently described. The curved rods 6 are bent into semi-circular formation and have their ends soldered or otherwise fixed to the corrugated flange 5. The ring 4, the flange 5, and the semi-circular rods 6 therefor, form a single removable unit that can be removed from the body of the sifter when desired. By snugly fitting the ring in the body, however, accidental or casual displacement of this removable element is prevented.

The screening element comprises an annular band 7 of a diameter less than the inner diameter of the body 1. The hemispherical screen 8 has its marginal edge fastened to the upper marginal edge of the band 7, the edge of the latter being bent upon itself to form gripping flanges for tightly engaging the marginal edge of the screen thereby securing the screen to the band so that when oscillatory movement is imparted to the band, the screen will be properly agitated. The annular rim 9 formed at the upper marginal edge of the band by thus providing the gripping flanges 75 for the screen, engages beneath the interior annular bead 3 to limit the upward movement of the sifting element as will presently appear. The lower marginal edge of the annular band 7 is turned inwardly and this in-turned portion is corrugated forming the fluted flange 10. This fluted flange rests upon fingers 11 formed by inturned ends of the wire rods 12 which are fixed to the lower end of the body and are preferably three in 90 number, two being shown in Fig. 1 of the drawing. The fingers 11 have the fluted flange 10 resting thereon and consequently when the sifting element is oscillated, the corrugations in the flange 10 will cause the 100 sifting element to rapidly vibrate thereby giving a vibratory and an oscillatory movement to the sifting element at the same time.

Oscillatory movement is imparted to the band 7 by an actuating element which comprises a knob or handle 13 formed at the end of a rod 14 which projects through a slot 15 in the body and is attached to the flange 7. The slot may be of any desired length and the operator may readily grip the knob with 105 one hand while the other hand engages the handle 2.

2

In operation, the flour will be placed in the sieve receptacle which is formed by the semi-spherical screen 8. The operator will then impart an oscillatory movement to the actuating element thereby causing the sifting element to oscillate. The engagement of the fluted flange 10 with the fingers 11 will cause the screen to rapidly vibrate and the combined vibration and oscillation of the sifting element will rapidly sift the flour. The tendency of the flour within the sieve, however, to move with the sieve as it is oscillated, is avoided by the corrugated flange and the semi-circular rods 6. The corrugations in the flange 5 engage the contents and assist the rods 6 which are disposed in close proximity to the inner surface of the sieve, to prevent movement of the flour with the sifting element and thereby facilitate the sifting operation.

The foregoing description and accompanying drawings have reference to what may be considered the preferred or approved form of my invention. I desire it to be understood that I may make such corrections in the construction and arrangement of parts, materials, dimensions, et cetera, as may prove expedient and fall within the scope of the appended claims.

Having thus fully described my invention what I claim as new and desire to secure by Letters Patent, is:—

1. A flour sifter comprising a body having a sifting element mounted therein, an annular band connected to the sifting element and means formed on the annular band to support the sifter element and to cause a

vibratory movement thereof when the annular band is oscillated.

2. A flour sifter of the character described, 40 comprising a body having a sifting element mounted therein, and an annular fluted flange formed on the sifting element, a plurality of inwardly projecting fingers carried by the body and engageable with the fluted 45 flange, and means to actuate the said sifting element.

3. A flour sifter comprising a body, a rotatable band mounted within the body, a screen element carried by the upper edge 50 of the band, a fluted flange formed on the lower edge of the band and means formed on the body and engageable with the fluted flange to support the band and impart vibrations to the band as the fluted flange is 55 moved over the said means.

4. A flour sifter comprising a body having a rotatable sifting element mounted therein and including a substantially hemi-spherical screen, means for imparting an oscillatory 60 movement to the screen, a corrugated flange depending partially into the screen, and semi-circular rods attached to the flange and slightly spaced from the interior surface of the screen to engage the contents of the 65 screen to prevent movement thereof while the said screen is oscillated.

In testimony whereof I affix my signature in presence of two witnesses.

FREDERICK Y. JENSEN.
